(57) **CLAIM**

The ornamental design for camera mounts for a radar gun assembly, as shown and described.

DESCRIPTION

FIG. 1 is a front perspective view showing an embodiment of a design for camera mounts for a radar gun assembly; FIG. 2 is a front view of FIG. 1;

FIG. 3 is one side view of FIG. 1;

FIG. 4 is another side view of FIG. 1; and,

FIG. 5 is a top plan view of FIG. 1.

The broken lines are directed to environment and are for illustrative purposes only; the broken lines form no part of the claimed design.

1 Claim, 3 Drawing Sheets
